UNITED STATES PATENT OFFICE.

WILLIAM H. STRINGFIELD, OF PHILADELPHIA, PENNSYLVANIA.

TROUSER-LEG SUPPORT.

Application filed March 21, 1928. Serial No. 263,383.

My invention relates to a trouser leg support adapted for use in undertaking establishments in the preparation of the dead for burial, and more particularly to a pant leg holder or pad adapted to be positioned between the top of the leg of the deceased and the trouser's leg, to impart to the leg of the trousers a smooth and neat appearance not otherwise obtainable.

It has been the practice heretofore in dressing a corpse for burial to stuff newspapers or the like between the legs of the deceased and the trouser legs to maintain the latter in proper shape.

It is the object of my invention to provide means for supporting and shaping the trouser legs of the deceased without the necessity of using paper or the like, which is not efficient or consonant with the dignity and sombre character of the occasion.

To the above ends, my invention consists in providing a novel trouser leg support or holder composed of a pad or form of a generally elongated, convex shape, and tapering from the thigh end to the ankle end to suit the varying thicknesses of different portions of the trouser leg, said pad or form having spring clips or the like at its forward end for holding the pad in place, said clips being adapted to engage the ankles of the deceased.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings in which:

Figure 1, represents a perspective view of a portion of a trouser's leg support embodying my invention, showing also its manner of application.

Figure 2, represents a longitudinal section on line 2—2, Figure 1, certain parts being shown in elevation.

Figure 3, represents on an enlarged scale a perspective view of my novel trouser's leg support shown detached.

Figure 4, represents a transverse section on line 4—4, Figure 3.

Similar numerals of reference indicate corresponding parts.

1 designates my novel construction of a trouser's leg support, the same comprising a bottom or base member or body portion 2, which may be of thin sheet metal, cardboard, vulcanized fibre or any other suitable stiff, rigid or unyielding material. This body portion is of concave contour at its bottom and may be provided with the reinforcements 3 such as the longitudinal flanges 3 and the end flanges 4, which may be separate from the body or if desired may be integral with the body and are deflected outwardly and then inwardly, as will be understood from Figures 3 and 4, and serve to retain in place the edges 5 of the fabric covering 6, between which and said body 2 is a filling or stuffing 7, which may be cotton, felt or the like, as will be understood from Figures 2 and 4.

The fabric 6 is preferably of dark or black material and the general contour of the holder or support is tapering, that is, the outer longitudinal edges converge from the left of Figure 3, to the right thereof so that a stiff, elongated form is produced, which extends about from the thigh 8 or crotch of the corpse substantially to the ankle 9 thereof as indicated in Figure 2. The forward or right hand end of the pad or form 1 is provided with spring clips or clamps, as indicated at 10, which are adapted to engage the ankles of the corpse to secure the pad or form in position. The pants or trouser legs are indicated at 11. In the construction seen in Figures 2, 3 and 4, the side and end reinforcements are formed of U-shaped members having the flanges 3 and 4, but as stated, said flanges may be integral with the body if desired. The pad or form can be first made from a flat blank and then bent to the desired contour, or it can be made curved as shown, and after the cover 6 and the filling 7 have been placed in position the edge and end reinforcements can be applied.

It will be apparent that after the corpse is otherwise prepared for burial and is dressed, the pads or forms 1 can be readily slipped into the space between the thigh and leg and the top of the trousers, whereupon the latter will appear neat and straight, as seen in Figures 1 and 2 and will give to the legs a neat appearance. The pad form or holder can of course be constructed of a single thickness of material if desired, and may

be pressed, formed or otherwise shaped into the contour seen in Figures 3 and 4, the essential feature of my invention being the provision of an elongated tapering body portion convex at its exterior and provided with suitable clips or fastening devices at its front or narrower end, and adapted to be inserted within the pant leg of a corpse and to be substantially co-extensive with the thighs and calves of the latter, whereby the pant legs will be caused to assume a neat and smooth appearance.

By occupying the space between the leg of the corpse and the leg of the trousers, my novel holder prevents the collapsing or wrinkling of the latter as will be apparent.

It will thus be seen that I have devised a new and useful trouser's leg holder which is not only highly efficient and performs a useful purpose, but one which is inexpensive to manufacture, thereby improving the appearance and dressing of a corpse without materially adding to the cost.

I am aware that the invention may be embodied in other specific forms without departing from the spirit or essential attri-

butes thereof, and I therefore desire the present embodiment to be considered in all respects as illustrative and not restrictive, reference being had to the appended claims rather than to the foregoing description to indicate the scope of the invention.

Having thus described my invention what I claim as new and desire to secure by Letters Patent, is:—

1. In a device of the character stated, an elongated form, convex on its upper surface, and adapted to fit over the leg and thigh of a corpse, said form being relatively rigid throughout its longest axis, and clips on the front of said form for securing said form to the ankle of said corpse.

2. In a device of the character stated, an elongated tapering padded form, convex on its upper surface and concave at its bottom surface, and adapted to fit over the leg and thigh of a corpse said form being relatively rigid throughout its extent, reinforcements for the edges of said form and spring clips at the front end of the latter for securing said pad to the ankle of said corpse.

WILLIAM H. STRINGFIELD.
